United States Patent Office.

JOHN SMITH, OF ENFIELD, ASSIGNOR TO HARTFORD CARPET COMPANY,
OF HARTFORD, CONNECTICUT.

Design No. 3,931, dated March 22, 1870.

DESIGN FOR A CARPET-PATTERN.

The Schedule referred to in these Letters Patent and making part of the same.

To all whom it may concern:

Be it known that I, JOHN SMITH, of the town of Enfield, county of Hartford, State of Connecticut, have invented or produced a new and original Design for a Pattern to be inwrought into three-ply ingrain and other Carpetings, in colors similar to those painted on the drawings accompanying this specification, or in other colors substituted in the place of those painted on the drawings herewith; and I do hereby declare that the drawings accompanying this specification do give and convey to any one skilled in the art of carpet-weaving a more defined and thorough description of the nature of my invention than it is

in the power of language otherwise to convey, and are sufficient to enable any one skilled in the art of carpet-weaving to use my invention.

What I claim as my invention, and desire to secure by Letters Patent, is—

The configuration of the design hereunto annexed, when made by being inwrought into three-ply ingrain or other carpeting; in the form similar to the drawings accompanying this specification.

JOHN SMITH.
